OTHER PUBLICATIONS Examination Report for AU 341324, 3 pgs., dated Oct. 24, 2012.
(Continued)Primary Examiner — Dominic V Simone(74) Attorney, Agent, or Firm — Morgan, Lewis & Bockius LLP(57) CLAIM

The ornamental design for a shoe with dual-outpatch sole, as shown and described.

DESCRIPTION

FIG. 1 is a perspective view of our new design of a shoe with dual-outpatch sole;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1; and,

FIG. 7 is a back view of the design of FIG. 1.

The broken lines depicting the back portion of the upper of the shoe with dual-outpatch sole are understood to be unclaimed environmental subject matter.

1 Claim, 6 Drawing Sheets# US D844,951 S
